UNITED STATES PATENT OFFICE.

JAMES MURPHY, OF LONDON, ENGLAND.

BOTTLE-BLOWING MACHINE.

1,042,129.

Specification of Letters Patent.

Patented Nov. 5, 1912.

Application filed July 25, 1910. Serial No. 573,615.

To all whom it may concern:

Be it known that I, JAMES MURPHY, a subject of the King of Great Britain and Ireland, residing at 69 Galloway road, Shepherds Bush, London, W., England, engineer, have invented certain new and useful Improvements in and Relating to Bottle-Blowing Machines, of which the following is a specification.

This invention relates to bottle blowing machines and has for its object to provide a machine of simple construction.

According to the invention I provide the glass blowing machine with two alternately operating and inversely disposed parison molds for each vertically disposed finishing mold, so that one of the parison molds is cooled while the other is in operation.

According to the invention moreover I provide two alternately operating bottom molds for each finishing mold said bottom molds being alternately and automatically brought into operation.

According to the invention moreover I provide a head or neck mold intermediate of the finishing mold and the parison molds and I rotatably mount the vertically disposed finishing mold, the inversely disposed parison molds and the head or neck mold upon a vertical shaft which serves simultaneously as the fulcrum for the finishing mold and the parison molds.

The invention is illustrated in the accompanying drawings which represent a machine constructed according to the invention.

Figure 1 is a side elevation of the machine showing the finishing mold, head or neck mold and a parison mold in the closed position. Fig. 2 is a front elevation corresponding thereto. Figs. 3 and 4 are a side elevation and plan respectively of the head or neck mold carrier. Fig. 5 is a front elevation of the parison molds and their carriers. Fig. 6 is a plan corresponding thereto showing one of the parison molds in the closed position. Fig. 7 is a similar plan showing the parison molds both open. Fig. 8 is a similar plan showing the second parison mold closed. Fig. 9 is a plan of a modified form of the parison mold carriers. Fig. 10 is a vertical section on an enlarged scale of the operating mechanism for the parison mold carriers shown in Fig. 9. Fig. 11 is a vertical longitudinal section on

an enlarged scale of the head or neck mold and the necessary parts for regulating the air supply and for moving the neck mold plunger. Fig. 12 is a sectional plan of the parts shown in Fig. 11. Fig. 13 is a side elevation of the head or neck mold provided with the levers for operating the same and for controlling the air supply. Fig. 14 is a plan corresponding to Fig. 13. Fig. 15 is a similar plan showing the head or neck mold open. Fig. 16 is a vertical section of a modified form of neck mold for the production of wide neck bottles. Fig. 17 is a plan view of the bottom molds and their operating gear. Figs. 18-22 show diagrammatically the various positions of the head or neck mold and the hand levers for operating the same.

In carrying the invention into effect I provide upon a frame 1 a vertically disposed shaft 2 which is adapted to support and act as fulcrum for all the molds. In the frame I provide a compressed air cylinder 3, the piston rod 4 of which is provided on both sides with rack teeth 5 and is mounted at its free end in bearings 6 in the frame. In the frame I also mount a trip lever 7 adapted to operate the inlet and outlet valves of the compressed air cylinder 3 and I provide means to adjust the said trip lever 7 in any required position, such for example as a pawl 8. On each side of the toothed portion 5 of the piston rod I provide a vertically disposed shaft 9 and 9^a upon each of which is keyed a toothed wheel H gearing with the racks 5. Upon these shafts I also provide two sets of toothed wheels 10 and 11 and 10^a and 11^a one set 10 and 10^a adapted to engage with corresponding toothed wheels 12 mounted in the carrier arms 13 of the finishing mold, and the other set 11 and 11^a adapted to engage with toothed wheels 14 mounted on the carrier arms 15 of the parison molds.

When in the position shown in Fig. 1 compressed air is admitted to the cylinder 3 at the rear of the piston the piston is moved against the action of a spring 16 and through the medium of its toothed piston rod 4 and the toothed wheels H rotates the vertical shafts 9 and 9^a through an angle of 90° and thus also the carrier arms 13 and 15 of the finishing and parison molds so that the molds, which each consists of two parts, are opened. If on the operation of the trip

lever 7 the compressed air is admitted to the cylinder 3 at the front of the piston the latter is moved rearward and the molds are closed.

5 The two parts of the vertically disposed finishing molds A are connected to the carrier arms 13 by means of U-shaped frames 17 which are adjustably secured to the carrier arms by bolts 18 mounted in lateral slots provided in the carrier arms. Through the ends of the U-shaped frames 17 pass bolts 19 provided with axial holes through which pass bolts 20 on which the mold parts are mounted so that they can be adjusted in 10 a vertical direction. The adjustment of the finishing mold parts is effected by means of lateral screws 21 which contact with the sides of the said mold parts.

The carrier arms 15 for the parison molds 20 are provided at their ends with vertically disposed bolts 22 on which are pivoted two levers 23, each provided with three branches. At the opposite ends of each of the triple branched levers are mounted, in a similar 25 manner to the finishing mold parts, the halves of one of the parison molds B, C. The central arms of the triple branch levers are connected by means of rods 24 to a stationary pivot 25 disposed in front of the vertical shaft 2 upon which the carrier arms 15 are mounted.

In the position shown in Fig. 6 the parison mold B, that is the halves thereof, are brought together. If the carrier arms 15 are moved outward by the rotation of the shafts 9 and 9^a then the two halves of the 30 parison mold are separated. These are simultaneously moved slightly to the rear on the carrier arms, as the fulcrum of the rods 24 is in advance of the fulcrum of the carrier arms 15 and thus moves the point of connection of the levers 23 and the rods 24 slightly behind a line passing through the fulcrum of the levers and the rods.

45 When the shafts 9 and 9^a are rotated in a reverse direction by the piston, the rods and the arms of the branched levers 23 connected thereto are moved to the rear and outward through an angle of 180°. In consequence of this the halves of a cool second 50 parison mold C are brought into the operative position while the halves of the hot parison mold B are moved outward and allowed to cool. On the further operation of 55 the machine this procedure is repeated, with the exception that now the parts of the parison mold B are moved toward one another and those of the parison mold C away from one another. It will be understood 60 that the rotation of the mold halves is always in the same direction.

In a modified form of construction (Figs. 9 and 10) for alternately bringing the parison molds into the operative and cooling 65 positions two forked arms 15^a and 15^b are

mounted on the vertical shaft 2 and at the ends of the forked arms are provided the halves of the parison molds B, C. On opening the mold B the other mold C is closed and on rotating the whole through an angle of 180° the closed mold C is brought into the operative position.

The head or neck mold D (Figs. 11-15) is provided at the end of an angular lever 30 cast integral with a compressed air cylinder 31 which is adapted to rotate in a sleeve 32 carried by a bracket mounted upon the vertical shaft 2. The head or neck mold D is composed of two parts which are moved toward or away from one another on inclined arms 30. This movement for opening and closing the head or neck mold as also the movement of the head or neck mold through an angle of 180° is effected by the operation of a handle 33 provided at the end of the inclined arm 30. This handle is forked and between its prongs 34 is provided a pin 35 on which it is adapted to rotate through an angle of 180° about a sleeve 36 mounted at the end of the arm 30.

The prongs 34 of the handle are connected to the front half of the neck or head mold D by short rods 37 and to the rear half of the neck mold by long rods 38. If the handle 33 (Fig. 13) is moved from its lowest position to its highest position the short rods 37 draw the front half of the neck or head mold forward and the long rods 38 push the rear half of the neck or head mold rearward thus opening the head or neck mold.

The piston 39 in the compressed air cylinder 31 for the head or neck mold is provided with an eccentrically disposed piston rod 40 of which the part projecting into the head or neck mold is formed as a rack 41 adapted to engage with a toothed part 42 of the screw plunger 43 provided in the head or neck mold. The central part of the plunger is provided with a screw thread 44 of the same pitch as a tap 45 which is to form the screw thread in the bottle neck and is adapted to screw into a lead or guide screw thread 46 in the neck or head mold. The piston 39 in the cylinder therefore rotates the tap 45 into and out of the neck or head producing portion of the head or neck mold on reciprocation.

Through the center of the compressed air cylinder 31 for the head or neck mold passes a tube 47 which is rigidly connected to a supply pipe 48 and cannot therefore rotate with the cylinder 31. The tube 47 is provided with a radial hole 49 which according to the position of the cylinder is adapted to correspond with an aperture 50 in the cylinder cover 51. The tube 47 passes tightly through the piston 39 and projects into a hollow in the cylinder base 52 to which is connected the air conduit 53 lead-

ing to the neck or head mold. This conduit is provided with a cock 54 which is operated by a rod 55 and a handle 56 pivoted to the handle 33 for operating the head or neck mold. From the cock 54 passes a second conduit 57 leading to a passage 58 in the cylinder base 52 through which air passes when the piston is to be moved backward. In the cylinder base is provided a 10 spring valve 59 of which the spindle projects into the path of the head or neck mold halves so that when the head or neck mold is opened the valve 59 is raised from its seat in order to allow the air in front of 15 the piston to escape.

For the purpose of permitting the head or neck mold to be used for large necked bottles I provide an exchangeable mold ring 66 (Fig. 16) which may be connected to the 20 head or neck mold by screws 65 and I mount a neck core 67 upon the tap.

Below the finishing mold I provide two automatically operating bottom molds 68 and 69 (Fig. 17) mounted at the ends of a 25 lever 70 pivoted at its center 71 where it is provided with a chain wheel 74 connected to a second chain wheel 75 mounted upon the vertical shaft 2 and driven through toothed wheel gearing 76 from one of the 30 two vertical driven shafts 9 and 9^a. In this manner the bottom molds are alternately cooled and brought into the operative position.

The operation of the machine is the following:—At the beginning all the parts are 35 in the position shown in Figs. 1, 2 and 18 in which position the head or neck mold D and the hand lever 33 are directed upward as shown in Fig. 1 in dotted lines; the 40 halves of the finishing mold A, and of the parison mold B are together and the head or neck mold, which is closed, and has the plunger projecting into the opening therein, closes the lower end of the parison mold D 45 while the bottom mold 68 closes the lower end of the finishing mold. Glass is now supplied to the parison mold B, the operator cuts off the glass and by operation of the hand lever 33 adjusts by means of the hand 50 lever 56 the air cock 54 in such a position that compressed air passes through the bore 58 to the front side of the piston 39. The piston is then moved backward and the rack 41 rotates the plunger 43 out of the mouth 55 of the parison. The operator now opens the compressed air passage 53 leading to the head or neck mold and compressed air is admitted through the tube 47. During the withdrawal of the plunger from the parison 60 compressed air enters the parison so that the glass which has not solidified can flow downward. When sufficient air has entered the parison the hand lever 56 is released and is brought into its original position by means of a spring and thus the inlet

for compressed air is closed. The trip lever 7 is now released by the pawl 8 Fig. 1; it is raised by the action of a spring 7^a and operates the inlet valve of the compressed air cylinder 3; the piston moves forward and the rack 5 by means of the toothed wheels H rotates the vertical shafts 9 and 9^a through an angle of 90° so that the finishing mold A and the parison mold B are opened, the latter assuming the position shown in Fig. 7, 70 thereupon the head or neck mold D with the parison together with the cylinder 31 is rotated through an angle of 180°. The trip lever 7 is now depressed and by operating the valve for the compressed air the piston 75 is moved back in the cylinder 3. The rack 5 rotates by means of the toothed wheels H, the shafts 9 and 9^a into their original positions; the finishing mold A is thus closed around the parison; simultaneously the 80 parison mold carriers 15 are also moved together whereby the connecting rods 24 rotate the three armed levers 23 carrying the halves of the parison molds through an angle of 180° so that the parison mold C is 85 now turned into operative position and closed (Fig. 8). By pressing the hand lever 56 compressed air is admitted into the parison in the finishing mold and the parison is blown out into the form of a bottle. By releasing the lever 56 the inlet for the compressed air is closed and the hand lever 33 is rotated upward in a plane containing the longitudinal axis of the cylinder 31 so that the two halves of the head or neck mold D 90 are moved from one another and the neck piece is released and projects freely from the finishing mold (Fig. 20). The rear half of the head or neck mold D while opening presses against the spindle of the valve 95 59 in the cylinder base 52 and opens this so that the piston 39 during its forward movement does not meet with any resistance. On rotating the hand lever 33 through an angle of 180° about the longitudinal axis of 100 the cylinder 31 the open head or neck mold is moved upward with the cylinder 31, Fig. 21, and in this movement the cylinder 31 is rotated in such a manner that the bore 50 in its cover 51 is brought into communication with the bore 49 of the air tube 47 and compressed air enters behind the piston 39 which on its forward movement again moves the plunger 43 outward to its original 105 position. The hand lever 33 is now rotated downward through an angle of 180° so that the head or neck mold is closed (Fig. 22) and is now again in the original position under the cooled parison mold 6, this is now 110 filled with glass, the parison blown and by releasing the trip lever 7 the parison and finishing molds are opened. The bottom mold 68 with the finished bottle standing thereon is now rotated through an angle of 115 180° and is replaced by the cooled bottom 120 125 130

mold 69. The head or neck mold with the parison is now again swung downward and the previous operations are repeated. By this manner of working it is possible to obtain within a certain time a larger number of bottles than it was possible with earlier machines of the same type and the quality of the goods is also superior as each mold for working the glass is at a suitable temperature. As the parison molds have time to cool very hot glass can be worked which is advantageous in the bottle blowing industry. By exchanging the bottom molds there is also the advantage (without having regard to their cooling) that the operator is independent of an assistant to remove the finished bottles and to place them in a cooling chamber. If the parison molds are of different sizes then it is possible on a machine to alternately produce bottles of different weight. If bottles with a hollow bottom (wine bottles) are to be produced then instead of the bottom molds 68 and 69 (Fig. 7) there is provided a rotating beam 70 which is adapted to be raised and lowered and is at one end provided with a flat and at the other with a hollow bottom. The parison is blown on the flat bottom the arm is then lowered and rotated and the hollow bottom which is now under the parison is raised and forced into the bottom of the parison.

What I claim as my invention and desire to secure by Letters Patent is:—

1. In a bottle blowing machine, the combination of a head mold, a finishing mold, two parison molds, and means for alternately moving the parison molds into the operative position.

2. In a bottle blowing machine the combination of a head mold, a finishing mold, two parison molds, means for alternately moving the parison molds into the operative position, and means for providing the bottle neck with a screw thread.

3. In a bottle blowing machine, the combination of a head mold, a finishing mold, two parison molds, means for alternately moving the parison molds into the operative position, two alternately operating bottom molds for the finishing mold, and means for operating said bottom molds.

4. A bottle blowing machine, comprising a shaft, two alternately operating parison molds, connected to said shaft, a finishing mold connected to said shaft and disposed between the parison molds and the finishing mold, and two alternately operating bottom molds.

5. A bottle blowing machine, comprising a shaft, two alternately operating parison molds, connected to said shaft, a finishing mold connected to said shaft, a head mold connected to said shaft and disposed between the parison molds and the finishing

mold, two alternately operated bottom molds, and means for forming a screw thread on the bottle neck.

6. In a bottle blowing machine the combination of a head mold composed of two parts, means for opening and closing said parts and for inverting said head mold, a finishing mold composed of two parts, means for opening and closing said parts, two parison molds for each finishing mold, each of said parison molds consisting of two parts, means for bringing the parison molds alternately into the operative position, two alternately operating bottom molds, and means for operating said bottom molds.

7. A bottle blowing machine comprising three vertical shafts, gearing connecting said shafts together, means for operating two of the shafts, levers on the other shaft, head mold and finishing mold halves mounted on said levers, T shaped levers mounted on the levers aforesaid, one half of each parison mold mounted on two of the arms of one of the T shaped levers, the other halves of the parison mold mounted on two arms of another T shaped lever, means for rotating the parison mold halves through an angle of 180° on the opening and closing of the parison molds, two alternately operating bottom molds, and means for operating said bottom molds, toothed wheels at the lower ends of two of the vertical shafts, a rack engaging with said toothed wheels, a cylinder, a piston within said cylinder, said piston being connected to said rack, and means for supplying compressed air to the head mold and to the last mentioned cylinder.

8. A bottle blowing machine comprising three vertical shafts, gearing connecting said shafts together, means for operating two of the shafts, levers on the other shaft, head mold and finishing mold halves mounted on said levers, T shaped levers mounted on the levers aforesaid, one half of each parison mold mounted on two of the arms of one of the T shaped levers, the other halves of the parison mold mounted on two arms of another T shaped lever, means for rotating the parison mold halves through an angle of 180° on the opening and closing of the parison molds, two alternately operating bottom molds, means for operating said bottom molds, toothed wheels at the lower ends of two of the vertical shafts, a rack engaging with said toothed wheels, a cylinder, a piston within said cylinder, said piston being connected to said rack, means for supplying compressed air to the head mold and to the last mentioned cylinder, and means for providing the bottle neck with a screw thread.

9. A bottle blowing machine comprising three vertical shafts, gearing connecting said shafts together, means for operating

- two of the shafts, levers on the other shaft, head mold and finishing mold halves mounted on said levers, T shaped levers mounted on the levers aforesaid, one half of each parison mold mounted on two of the arms of one of the T shaped levers, the other halves of the parison mold mounted on two arms of another T shaped lever, means for rotating the parison mold halves through an angle of 5
- 10 180° on the opening and closing of the parison molds, two alternately operating bottom molds, means for operating said bottom molds, toothed wheels at the lower ends of two of the vertical shafts, a rack engaging with said toothed wheels, a cylinder, a piston within said cylinder, said piston being connected to said rack, means for supplying compressed air to the head mold and to the last mentioned cylinder, a screw plunger 15 and means for imparting a screw movement to the plunger.
10. A bottle blowing machine comprising three vertical shafts, gearing connecting said shafts together, means for operating two of the shafts, levers on the other shaft, head mold and finishing mold halves mounted on said levers, T shaped levers mounted on the levers aforesaid, one half of each parison mold mounted on two of the arms of one of the T shaped levers, the other halves of the parison molds mounted on two arms of another T shaped lever, means for rotating the parison mold halves through an angle of 180° on the opening and closing of 20 the parison molds, two alternately operating bottom molds, means for operating said bottom molds, toothed wheels at the lower ends of two of the vertical shafts, a rack engaging with said toothed wheels, a cylinder, a piston within said cylinder, said piston being connected to said rack, means for supplying compressed air to the head mold and to the last mentioned cylinder, a screw plunger 25 and means for imparting a screw movement to the plunger, consisting of a compressed air cylinder, a piston located within said cylinder, a rack connected to said piston and operating said plunger, a valve on said cylinder and means for operating said valve.
11. In a bottle blowing machine the combination of a head mold composed of two 30 parts, means for opening and closing said
- parts and for inverting said head mold, consisting of inclined planes on which the head mold halves are mounted, a pivoted handle, levers connecting said handle to the respective head mold halves, a finishing mold composed of two parts, means for opening and closing said parts, two parison molds for each finishing mold, each of said parison molds consisting of two parts, means for alternately bringing the parison molds into 35 the operative position, two alternately operating bottom molds, and means for operating said bottom molds.
12. A bottle blowing machine comprising three vertical shafts, a gearing connecting said shafts together, means for operating two of the shafts, levers on the other shaft, head mold and finishing mold halves mounted on said levers, T shaped levers mounted on the levers aforesaid, one half of each parison mold mounted on two of the arms of one of the T shaped levers, the other halves of the parison molds mounted on two arms of another T shaped lever, means for rotating the parison mold halves through an angle of 180° on the opening and closing of 40 the parison molds, two alternately operating bottom molds, means for operating said bottom molds, toothed wheels at the lower ends of two of the vertical shafts, a rack engaging with said toothed wheels, a cylinder, a piston within said cylinder, said piston being connected to said rack, means for supplying compressed air to the head mold and to the last mentioned cylinder, a screw plunger 45 and means for imparting a screw movement to the plunger, consisting of a compressed air cylinder, a piston located within said cylinder, a rack connected to said piston and operating said plunger, a valve on said cylinder and means for operating said valve.
- In testimony whereof I have hereunto signed my name to this specification in the presence of two subscribing witnesses.
